ATTORNEY

UNITED STATES PATENT OFFICE.

AUGUST SONNTAG, OF STEINWAY, NEW YORK, ASSIGNOR TO WEINER BROTHERS, OF NEW YORK, N. Y., A COPARTNERSHIP.

DESIGN FOR A TEXTILE FABRIC.

51,290.

Specification for Design.

Patented Sept. 18, 1917.

Application filed May 16, 1917. Serial No. 169,144. Term of patent 3½ years.

To all whom it may concern:

Be it known that I, AUGUST SONNTAG, a citizen of the United States, residing at No. 398 Ditmore avenue, Steinway, in the county of Queens and State of New York, have invented a new, original, and ornamental Design for Textile Fabrics, of which the following is a specification, reference being had to the accompanying drawing, forming part thereof.

The figure is a plan view of a piece of textile fabric, showing my new design.

I claim:

The ornamental design for a textile fabric as shown.

AUGUST SONNTAG
